UNITED STATES PATENT OFFICE.

EDWARD HOLZWORTH, OF ALLIANCE, OHIO.

SPARK-PLUG.

1,093,423.

Specification of Letters Patent. Patented Apr. 14, 1914.

Application filed April 9, 1912. Serial No. 689,564.

To all whom it may concern:

Be it known that I, EDWARD HOLZWORTH, a citizen of the United States, residing at Alliance, county of Stark, and State of Ohio, have invented certain new and useful Improvements in Spark-Plugs, of which the following is a specification.

This invention relates to spark plugs.

My object is to provide a spark plug of simple, strong and durable construction having its parts arranged for ready separation so that it may be thoroughly cleaned when desired, and further, to provide a spark plug having electrodes constructed and arranged in a new manner, as also to provide packing, whereby certain parts of the plug are kept free from carbon and the reliability of the plug is insured.

One embodiment of the invention is set forth hereinafter and its novel features are recited in the appended claim.

In the accompanying drawings:—Figure 1 is a side elevation; Fig. 2, a longitudinal section; Fig. 3, a side elevation of the stem and parts carried thereby; Fig. 4, a section on line 4—4, Fig. 3; and Fig. 5, a detail of a connector.

The spark plug has a metallic, tubular part provided with a screw-threaded end 1 adapted to afford means of connection to the engine, a nut 2 by which the plug may be turned, an internal shoulder 3 and an external screw threaded part 4.

The insulating or porcelain stem 5 has a reduced bifurcated part 6 which passes centrally through the part 1, the shoulder 7 bearing against asbestos packing 8 interposed between said shoulder and the shoulder 3. This packing prevents the entrance 35 of carbon to the interior of the plug beyond the shoulder 7. On the reduced part 9 which terminates in a shoulder 10, is a nut 11 which is adapted to bear against the shoulder 10 and to engage the screw threaded part 4, thereby holding the stem 5 in position, the shoulders 7 and 10 preventing any endwise movement of the stem 5.

Extending through the stem 5 is a rod 12 which has a cap 13 and binding nuts 14 at

one end and at its opposite end is provided 50 with an electrode 15 disposed at one side of the bifurcated part 6. Between the electrode 15 and the end part 6 is an asbestos or isinglass washer 16, the latter constituting a packing to prevent the entrance of carbon to the bore containing the rod 12. Extending through a bore in the porcelain stem 5 is a rod 17 which terminates in an electrode 18, disposed opposite the electrode 15 and at the other side of the bifurcated part 6. 60 Between the electrode 18 and the end of the part 6 is an asbestos or isinglass washer 19. The bifurcated part 6 provides a clear spark gap and also facilitates the voiding of carbon from the electrodes. The rod 17 65 extends through shoulder 10 and is provided with a clamping nut 20 which is located in a cut out portion 21 in the stem and is disposed against a piece of asbestos or isinglass 22 arranged in said cut out 70 part. The stem 17 passes through a metallic contact member 23 which is held by the clamping nut 20 in the cut out part 24 of the stem. This contact member is preferably of copper and the part thereof which 75 overhangs the enlarged part of the stem bears against the interior wall of the screw-threaded part 4 thereby placing the rod 17 in circuit with the engine frame.

The asbestos or isinglass washers or pieces 80 prevent the accumulation of carbon on the bores through which the rods 12 and 17 pass and the provision of the asbestos or isinglass piece 22 further prevents the escape of any carbon which may have entry to the 85 bore for the rod 17.

The parts may be readily separated for purposes of cleaning.

Having thus described my invention, what I claim as new and desire to secure by Letters Patent, is:

In a spark plug, the combination with an inner insulating stem having an enlarged shouldered part intermediate its ends, of an outer metallic two-part attaching member 95 for securing the plug to the engine, said attaching member being engaged with the enlarged part of the stem, a terminal extend-

ing through the stem and provided with an electrode, another terminal having an electrode and extending through the enlarged part of the stem and emerging from the shouldered portion of said enlarged part, a clamping device for holding the last named terminal in position, and a contact member held by the clamping device and

engaged with the two-part attaching member.

10

In testimony whereof, I hereunto affix my signature in presence of two witnesses.

EDWARD HOLZWORTH.
